UNITED STATES PATENT OFFICE.

ROBERT SYKES MULLER, OF MONTREAL, QUEBEC, CANADA.

AWNING.

Application filed December 19, 1927. Serial No. 241,227.

This invention relates to new and useful improvements in awnings for window openings and the like, and the object of the invention is to provide an awning which will be simple to manufacture, easy to erect in position, and easily adjusted to suit the size of window openings.

Another object is to provide a collapsible awning which will allow at all times free passage of air through the opening to which it is fitted.

A further object is to provide an awning which will be easily adjusted to suit weather conditions, or raised to clear the opening when required.

According to my invention I provide a channel of box shaped section with slotted guides which may be secured to the side frames of a window, door, or the like. Slidably mounted in the guides are the curtain supports which each consist of a bent bar, pivotally mounted on a horizontally disposed bar, the ends of which are provided with means to position the horizontal bar between the guides. Both bars of each curtain support are provided with means to allow adjustments to be made to suit the width of the window openings. Tie bars are provided between each horizontal bar and the bent bar, to hold them a predetermined distance apart, so that the curtain which is made of duck or such like flexible material may be stretched therebetween. The ties hold the curtains in such a manner that the lower curtains may be raised and partially covered by the curtain immediately above it when the awning is in the closed position when not in use. Stiffening means are provided for the lowermost curtain to hold it in shape, while supporting the curtains above it, and means are provided for holding the curtain sections a predetermined distance apart. Means are also provided for suspending the curtains and for raising or lowering the awning.

In the drawings which illustrate my invention:—

Figure 1 is a front perspective view of an awning attached to a window frame.

Figure 2 is a back perspective view of an awning attached to a window frame.

Figure 3 is an enlarged part perspective view of the awning showing the lower sections.

Figure 4 is a perspective view of part of one of the curtain supporting frames.

Figure 5 is a perspective view of one of the guide members.

Figure 6 is a perspective plan of the guide member at the top thereof.

Referring more particularly to the drawings, 11 designates the side frames, 12, the lintel, and 13 the sill of a window. Secured to the side frames by any suitable means are the guides 14 which are preferably of square tubular cross section, each having a slot 15 formed in one side. The slot extends from one end 16 of each of the frames to a point in close proximity to the other end 16^a. Also formed in the guides at the ends 16^a are the holding slots 17 which are spaced from the ends 18^a of the slots 15. Resting in the slots 17 and extending between the guides is the horizontally disposed curtain supporting rod 18. Suitable guide washers 19 are secured to the rod in proximity to its ends to hold the rod in the guides. Four rods 20 similar to the rod 18 are mounted in the slots 15. Each of said rods fits into a sleeve 21 and is made in two sections so that the rod may be quickly adjusted to suit the distance between the guides. Hingedly attached to the rods 20 are the curtain forming members 22, which are made of flat bars 23 made in the form of three sides of a rectangle. The members 22 are each made in two sections joined together by the bolts or rivets 24. One of the sections is provided with a plurality of rivet holes to allow the members to be adjusted to suit the distance between the guides. Extending between the upper rod 18 and the forming members in proximity thereto, are the tying members, or member 25, which hold the curtain in shape. Similar tying members 26 are provided between the rods 20 and the forming member immediately below them, and between the lowermost rod and the lowermost framing or forming member 27. The member 27 is of similar construction to the members 22, but is hingedly attached to spacer or stiffening members 28 hingedly attached at one end to the lowermost rod and at the other end slidably mounted in the guides, the last mentioned ends being recessed to fit into the guides. Each of the tying members is made of flat bars, the ends of which pass through slots formed in the rods and the forming members in proximity thereto. The curtains 29, which are preferably made of duck, are stretched between the forming members and the rods immediately above

them, and the ends are brought into close proximity to the guides to prevent the glare of the sun from entering through the opening which the awning is covering when in the open position. Tensioning chains or such like flexible members 33 are provided between the horizontal rods to hold them a predetermined distance apart when the awning is in the open position, and such members may be covered by forming pockets 34 in the side portions of the curtains. A double pulley block 31, or a single pulley block 31^a, is mounted on the window frame in proximity to the upper end of each guide, and ropes 32 may be reaved therethrough and attached to the bottom rod 20, so that when the ropes are pulled, the curtains are pulled towards the top of the frame. One of said ropes may be passed through the double pulley block and joined to the other rope, so that the device may be controlled from one side of the window frame.

In erecting the device, the rods 20 are placed in the guide slots and the rod 18 is kept clear of the guides, as shown in dotted lines in Figure 5. The rods are then pushed upwardly in the guides and the rod 18 is slipped into the slots in the upper end thereof. A locking pawl 36 is provided to hold the upper rod in position. By pulling on the ropes, the curtain may be raised to clear the window opening with the lowermost portion of the curtain holding the upper portions in shape. As will be seen the device is simple in construction and easily erected and provides a device which will keep the glare of the sun from entering through the opening without interfering with the air space. The pawls 35 keep the upper rod from being pulled out of place by the upward movement of the curtain.

Having thus described my invention, what I claim is:—

1. In an awning structure, guides secured to the side frames of a window, said guides having each a recess formed at the top and a slot formed in the bottom, said slot extending upwardly to a point in proximity to the top of the guides, a top curtain rod resting in said recesses and extending between the guides, curtain supporting rods slidably mounted in the slots, flexible means connecting the rods together to hold them in spaced relationship, and means to pull the rods towards the top of the guides.

2. In an awning structure, guide members secured to the side frames of a window, said members each comprising a square tubular member having a recess at the top in one side thereof, and a slot extending from the bottom on the same side to a point in proximity to the recess, a curtain supporting rod extending between the guides and resting

on the recesses, and curtain rods flexibly attached to one another and slidably mounted in the slots. 65

3. In an awning structure, guide members secured to the side frames of an opening, said members each comprising a square tubular member having a recess formed in one side at the top of the member and a slot in the same side extending from the bottom to a point in proximity to the top, and adjustable curtain supporting rod extending between the guides and resting in the recesses in the guides, a plurality of adjustable curtain supporting rods slidably mounted in the slots, metallic flexible tying means between said rods and means for raising the rods towards the top of the frame. 70 75 80

4. In an awning structure, guide members secured to the side frames of a window opening, said members comprising tubular members each having a recess at the top thereof, and a slot extending from the bottom to a point in proximity to the recess, and an adjustable rod resting in the recesses, means for holding the top rod in the recess, adjustable rods slidably mounted in the slots and connected together, and to the top rod by flexible tying members, adjustable curtain forming members pivotally secured to the rods in proximity to the guides, and curtains between the forming members and the rods immediately below them, and covering the flexible tying members and stiffening members for holding in shape the bottom curtain. 90 95 100

5. In an awning structure, guide members secured to the side frames of a window opening, said members comprising tubular members each having a recess at the top and a slot extending from the bottom to a point in proximity to the recess at the top, an adjustable awning supporting rod extending between the guides and resting in the recesses, pawl means to hold the top rod in position in the recess, a plurality of adjustable curtain rods slidably mounted in the slots and flexibly suspended on chains from the upper rod, adjustable curtain forming members pivotally secured to each of the lower rods, flexible tying members between each of the curtain forming members and the rods immediately above them, means to raise the lower rods in the guides, and curtains between the horizontal bars and the curtain forming members immediately below them, said curtain having side pockets adapted to cover the tying members between the horizontal rod and stiffening members between the bottom rods. 105 110 115 120

In witness whereof, I have hereunto set my hand.

ROBERT SYKES MULLER.
